UNITED STATES PATENT OFFICE.

WILLIAM F. HENDRY, OF OSSINING, NEW YORK, ASSIGNOR TO MANHATTAN ELECTRICAL SUPPLY COMPANY, INCORPORATED, OF NEW YORK, N. Y., A CORPORATION OF MASSACHUSETTS.

CONNECTER FOR ELECTRICAL CONDUCTORS.

Application filed January 7, 1924. Serial No. 684,784.

This invention relates to new and useful improvements in connecters for electrical conductors, and more particularly to a connector adapted for use with push-button switches or the like and as a connecting clip or binding post. 55

With this object in view, the connector forming the object of the present invention is so constructed that it may be used in a 10 push-button switch or the like without the necessity of providing screws, rivets, etc., whereby the switch structure will be materially simplified.

The new and improved connector is adapted 15 for use also as a binding post on panels, dry cells, etc.; it may be attached in a readily accessible manner and forms a good connecting post for a large number of wires of various gauges.

20 The invention will be more clearly understood from the following detailed description of a preferred embodiment thereof and the appended claims.

In the drawings, Fig. 1 is a vertical cross 25 section of a push-button switch in which the new and improved connector is used;

Fig. 2 is a bottom view of such switch;

Fig. 3 is a top plan view of the switch with the bell or casing removed;

30 Fig. 4 is a perspective view of two connectors formed in accordance with the present invention and mounted in a push-button switch;

Fig. 5 is a sectional view along lines 5—5 35 of Fig. 3; and

Fig. 6 is a perspective view of three connectors mounted on a panel board.

The push-button switch structure consists 40 of a bell-shaped casing 1 having an aperture in its top through which a button or plunger 2 of insulating material projects. The plunger 2 has a collar 3 which engages the inside of the casing 1. The lower part of the casing 1 is flared out at 4, forming 45 a shoulder on which may rest a strip of insulating material 5. The strip 5 is formed into the shape clearly illustrated in Fig. 1 and is held within the downwardly projecting skirt 8 by indentations 6, 7 formed there-

50 in. Furthermore, the strip 5, as well as the flared-out portion 4 of bell 1, are perforated at 9, permitting the fastening of the push-button switch to a panel and the holding together of the strip of insulation 5 and the

bell 1. The insulating piece 5 is provided with notches 10 and 11 and two parallel oblong slots 12 and 13 near the center of the insulating piece 5, the slots and the notches being substantially in alignment with each other. 60

The connector proper is made of a continuous piece of resilient wire, bent to form an S 14, the end of the S being bent up and continued up to the top of the S. The upwardly projecting tail of the S is at an angle 65 of about 45° to the vertical axis of the S 14. From there the wire is bent outward at an angle of about 90° with the upwardly projecting tail of the S. It is formed into an ear 15, the end of which is in line with the vertical axis of the S. The wire is brought back into line with the head of the S and then doubled back at 16, the doubled-back portion 16 extending at such an angle that the lower portion of the S 14 falls between the 70 two legs of the doubled-back portion 16, but is normally in a somewhat higher plane. The upper part of the S 14 and the doubled-back portion or ear 15 are normally in substantially the same plane. 75

The clip or connector, when used in a push-button switch or the like, is assembled in the following manner: The clip is pushed over a sheet or strip of insulating material 5, with the lowermost portion of the S 14 engaging 80 the upper and the doubled-back portion 16 the lower surface of the strip of insulation 5. The clip is then pushed inwardly until the turned-down portion 17 of the wire falls within notch 10 or 11. At this time the lowermost portion of the S 14 is above the notch 12 or 13. However, the notch is not long enough to permit the lower portion of the S readily to fall through it. It is necessary to push back the S 14 against the resiliency 85 of the ear 15, whereupon the S will snap into place with its upper end engaging the upper surface and its lower protruding portion engaging the lower surface just adjacent to one end of the notch 12 or 13. The resiliency of the connector is placed under sufficient strain firmly to hold it in place as a self-contained unit. 95

A second clip may now be put in place in exactly the same manner as above described. 100 However, it will be shoved in from the opposite side of the insulating strip 5 than in the previous case, whereby the ears 15 of the

two clips will be in alignment with each other (Fig. 3). At this stage of the assembly the ears 15 will contact with each other, because both are substantially in the same plane. It will be necessary slightly to force up one of the ears 15 (see Fig. 1) to separate it from the other and, if the device is used in a push-button switch at a sufficient angle for it to engage the plunger 2 and hold it with collar 3 engaging the casing. By means of the button 2 the two ears may be forced to contact with each other, the button being returned to normal by the resiliency of the connector clip. When the push-button switch is placed into service the conductors 20 are connected and held in place by forcing one end of the wire formed into the doubled-back portion 16 up against the lower surface of the strip 5 (see the position indicated in dotted lines in Fig. 5) until the lower part of the S 14 projects between the two legs of 16. The wire 20 is now inserted through the eye formed by the lower part of the S 14 and when the bent-back portion 16 is released, it will firmly clamp the wire in place in good contact with the connector. The two ends of the wire constitute thus a separable resilient clamp for conductors which clamp is tightened when the push button is depressed.

Fig. 6 illustrates the manner in which a plurality of connector clips may be mounted on a board 21 by means of screws 22, so as to serve as connecting terminals or binding posts for wires 23. Inasmuch as the ears 15 are bent at an angle of about 45° to the doubled-back portion 16, the clip may be easily fastened to a board with the screw 22 all the time accessible. A large number of wires of various sizes may be connected through one binding post and wires may be connected to any other part of the connector clip. Obviously, the connector clip may be mounted on panels also in the manner illustrated in Figs. 1-5. In this case the ear 15 serves as the soldering terminal for one conductor and the S as the connecting point of a second conductor.

In addition to the above enumerated advantages, it should be noted also that the connector constructed in accordance with the present invention takes a firm grip of a conductor because the resiliency of a relatively long piece of wire is utilized within a relatively small space. Furthermore, the forming of such connector clips is a simple and inexpensive automatic operation, the cost of manufacturing being further reduced because only one type of connector need be manufactured for a great variety of uses.

The invention readily lends itself to a variety of modifications without departing from the spirit thereof. The gauge of the wire in the connector should be selected with

a view to the use that will be made of it, the convolutions and the form generally of the connector may be changed to suit the requirements encountered, etc.

What I claim is:

1. In a switch, a casing, a plunger of insulating material projecting therethrough and adapted to perform a limited movement with respect thereto, a strip of insulation within said casing, two notches provided in opposite sides of said insulation, two parallel slots in said insulation, each substantially in alignment with one of said notches, two connectors each formed of a single piece of resilient wire bent into an S, an ear, a bent-down and doubled-back portion, the doubled-back portion being in alignment with but normally in a different plane than the S and the ear being normally in substantially the same plane as the upper part of the S and at an angle thereto, each connector being held in place by the lower portion of the S protruding through a notch and the bent-down portion lying within the corresponding notch, a conductor being clamped within the loop formed by the lower portion of the S by the doubled-back portion, and the plunger being held in its uppermost position by one of the ears which has been bent up out of contact with the other ear.

2. A connector for electrical conductors comprising an insulating base having two holes therein and a pair of wire clips, each of said clips being formed of a single piece of resilient wire having one end bent into a loop which projects through and grips the edges of one of the holes in said base, the other end of said wire being bent at an angle around said base and formed into a loop through which the end of said first mentioned loop projects, and the middle of said wire being bent into a third loop, the third loop of one of said clips being positioned over and spaced from the third loop of the other of said clips whereby a push button switch is formed.

3. A connector for electrical conductors comprising a strip of insulation having a hole therein, and a piece of wire having a loop at one end thereof positioned within the hole, said loop being deformed to secure the loop in said hole, the other end of said wire being formed into a loop and bent around the edge of the said strip and positioned around the first mentioned loop so as to secure a conductor between the first and second mentioned loops, and a third loop formed in said wire intermediate the ends thereof whereby when pressure is exerted on the said third loop the grip of the first and second mentioned loops on the said conductor is tightened.

In witness whereof, I hereunto subscribe my name this 3rd day of January, 1924.

WILLIAM F. HENDRY.
